UNITED STATES PATENT OFFICE.

ROBERT S. GOULD, OF EAST ORANGE, NEW JERSEY.

DESIGN FOR A CURTAIN-POLE OR STAIR-ROD.

SPECIFICATION forming part of Design No. 16,054, dated April 21, 1885.

Application filed April 18, 1884. Term of patent 14 years.

To all whom it may concern:

Be it known that I, ROBERT S. GOULD, of East Orange, in the county of Essex and State of New Jersey, have invented a new and original Design for Curtain-Poles, Stair-Rods, &c., of which the following is a full, clear, and exact description, reference being had to the accompanying drawings, making part of this specification, in which—

10 Figure 1 represents a side elevation; and Fig. 2, a vertical transverse section of the same on line *x x*, Fig. 1.

The design relates to curtain-poles, stair-rods, and similar articles.

15 A in the drawings represents a curtain-pole, stair-rod, or other article, which consists of a straight cylindrical tube the contour of which is uniform throughout its length, said tube

having a series of symmetrical ornamental perforations or openings, *a*. The appearance 20 of the curtain-pole is thereby rendered lighter and more ornamental.

Having thus described my design, I claim as new and desire to secure by Letters Patent—

A design for curtain-poles or stair-rods, consisting of a straight cylindrical tube the contour of which is uniform throughout its length, said tube having symmetrical ornamental openings, substantially as shown and described.

In testimony that I claim the foregoing as 30 my invention I have signed it this 15th day of April, 1884.

ROBT. S. GOULD.
